U. S. Patent Office. Dec. 24, 1883.

UNITED STATES PATENT OFFICE.

HERMAN IHLENBURG, OF PHILADELPHIA, PENNSYLVANIA, ASSIGNOR TO
DAVID WOLFE BRUCE, OF NEW YORK, N. Y.

DESIGN FOR A FONT OF PRINTING-TYPE.

SPECIFICATION forming part of Design No. 13,871, dated April 24, 1883.

Application filed March 23, 1883. Term of patent 14 years.

To all whom it may concern:

Be it known that I, HERMAN IHLENBURG, (assignor to DAVID WOLFE BRUCE,) of Philadelphia, in the county of Philadelphia, Pennsylvania, have invented and produced a new and original Design for a Font of Printing-Type, of which the following is a specification.

The nature of my design is clearly shown in the accompanying typographic impression, to which reference is made; and it consists of an unshaded letter, having the triangular ornamentation at top and bottom of the up and down portions, as shown. In the C, E, F, G, S, and T, the triangular termination at the upper right-hand corner is crossed by the inclined line extending downward, and in the case of the E, M, and 2 this inclined line extends upward from the lower triangular ornament at the base of the letter upon the right. The

cross-line of the A and H curves upward and terminates upon the left in the dot. In the B and R the rounding portions of the letters are looped, as shown. The second form of the A, the H, K, the second form of the N and the X are extended below the line, and the second form of the N, the U, V, W, and Y are extended above the line upon the right.

The character of the design is preserved in the symbols, punctuation - marks, and the numerals.

Having now described my invention, I claim as new—

The design for a font of printing - type, as shown and described.

HERMAN IHLENBURG.

In presence of—

WILLIAM V. H. HICKS,
A. SIDNEY DOANE.
